UNITED STATES PATENT OFFICE.

ROBERT A. BROOKS, OF CHICAGO, ILLINOIS.

SURFACE DISCHARGE APPARATUS FOR TANKS.

1,203,578.

Specification of Letters Patent.

Patented Nov. 7, 1916.

Application filed January 22, 1913. Serial No. 743,481.

To all whom it may concern:

Be it known that I, ROBERT A. BROOKS, a citizen of the United States, residing at Chicago, in the county of Cook and State of Illinois, have invented a certain new and useful Improvement in Surface Discharge Apparatus for Tanks, of which the following is a description, reference being had to the accompanying drawings, forming part 10 of this specification.

My present invention is in the nature of an improvement upon that described and claimed in Letters Patent of the United States No. 1,040,872, granted to me on Oct. 15 8th, 1912, as hereinafter more fully set forth and particularly pointed out in my claims.

My present invention, like my former one, relates to a combined surface feeder and strainer for feeding gasolene from supply 20 tanks to gasolene engines or the carbureters thereof, and has for its object the provision of an improved feeding device of this character by means of which the gasolene is not only withdrawn from the upper part 25 of the supply in the tank near the surface thereof, instead of being withdrawn from the lower part thereof, which naturally holds the greatest amount of sediment and foreign matter, but effectively excludes from 30 the supply withdrawn from the tank even such foreign matter as may be carried in the upper part thereof, as well as any water which may be contained in the gasolene.

In the accompanying drawings Figure 1 35 is a vertical section of one end of a gasolene tank showing my novel feeding device in elevation therein; Fig. 2 a perspective view of the base plate of my novel device and some of the parts carried by it; Fig. 3 a 40 vertical section of the parts shown in Fig. 2 in the plane indicated by the dotted lines 3-3 of Figs. 1 and 2; Fig. 4 a perspective view corresponding with Fig. 2, but showing a modified construction in which the base 45 plate supporting the operating parts is detachably secured to the bottom of the tank; Fig. 5 a vertical section corresponding to Fig. 3, but showing the modified construction of Fig. 4; Fig. 6 a sectional detail of Fig. 4 in 50 the plane of the dotted lines 6-6 of said figure; Fig. 7 a sectional detail of the float and strainer and upper end of the delivery pipe by which they are carried; Fig. 8 a perspective view of the strainer or filtering 55 device of Fig. 7; and Fig. 9 a sectional de-

tail of Fig. 3 on the dotted lines 9-9 of that figure.

The same letters of reference are used to indicate corresponding parts in the several views.

The tank A, containing the supply of gasolene, is provided in its bottom with an opening B, circular in form in the present instance, the closure for which opening is formed by what may be termed the base 60 plate or supporting plate C of my novel feeding device. This plate C is likewise circular in form in the present instance, and is provided, at a suitable distance within its periphery, with an annular shoulder which 65 projects into and fits within the circular opening B in the bottom of the tank, the plate as a whole being firmly secured to the bottom of the tank by brazing or sweating its upper surface, outside the annular shoulder c, to the under surface of the tank surrounding the opening B therein. The plate C is provided upon its under surface with two integral and internally threaded 70 depending tubular bosses D, E, the former of 75 which constitutes a drainage outlet for the tank and carries a drain-cock d, shown in Fig. 1, while the latter constitutes the delivery outlet through which the gasolene is fed from the tank to the engine or other 80 point of consumption, the lower portion of the boss E being reduced and externally threaded at e, for the connection of the 85 delivery pipe.

Screwed into the internally threaded upper portion of the boss E of the base plate 90 C is the short vertically extending tubular arm f of an elbow-shaped casting F whose laterally projecting arm or portion f' consists of an enlarged cylindrical housing and 95 bearing for a hub G which has secured in it the lower end of the delivery pipe H, Fig. 1, which carries at its upper end the float I. The cylindrical member f' of the casting F is provided, in what may be termed its forward side Figs. 2 and 4, with a segmental slot f² through which the lower end of the 100 delivery pipe H projects and in which it may have vertical play (limited by the length of the slot), as the float I rises and falls with the level of the gasolene in the tank A.

The hub G, which carries the delivery pipe H and float I is provided upon its inner end with a reduced extension or pro- 110

jecting sleeve g , Fig. 3, which fits within a corresponding bore in the horizontal portion of the casting F and furnishes communication for the delivery pipe H through the hub G , to the delivery passage within the vertical arm f of the casting F and the coincident passage in the lower reduced end of the boss E . Under this construction gasoline admitted to the upper end of the delivery pipe H may flow through the same and out of the tank through the hub G and the passages in the casting F and boss E . A packing washer G' interposed between the hub G and the end wall of the housing f' , around the sleeve g , prevents escape of gasoline from the tank except through the delivery pipe H and its communicating passage through the hub G and casting F .

The construction of the combined float and strainer or filter which I preferably employ is best shown in Figs. 7 and 8, where the body of the float I is shown as consisting of a sheet metal cup I , approximately square in longitudinal section in the present instance, whose circular wall, adjacent its open end, is spun outwardly, at i , to form a receptacle and seat for the closed end or bottom of a shallow cup I' which is brazed or otherwise secured in the enlarged end of the first mentioned cup. The strainer or filter J , Fig. 8, is in the present instance of similar size and shape to the shallow cup I' , of the float, being of sufficiently less diameter than said cup to fit snugly within the same as shown in Fig. 7, with its open end abutting against the bottom of said cup and its closed end serving to close the open end of the cup I' and serve as a strainer for the gasoline entering said cup. The strainer J is provided with an opening j for the passage through it of the upper end of the delivery pipe H , which is externally threaded and screwed into the outer end of an internally threaded boss or sleeve I^2 which is secured at its inner end, by brazing or otherwise, to the bottom of the shallow cup I' . The boss or sleeve I^2 is provided in its opposite sides, adjacent the bottom of the cup I' , with openings i^2 through which the gasoline may flow from the cup I' into the upper end of the delivery pipe H .

The combined float and strainer, together with the delivery pipe H , are of such gravity that the float will rest in the upper portion of the gasoline within the tank A at such depth as to sufficiently submerge the strainer J and open end of the cup I' within the gasoline, as shown in Fig. 1, and the latter will flow through the strainer J and into the upper end of the delivery pipe H , and pass thence through the same and its supporting hub G to the passages in the casting F and boss E , and the pipe leading to the engine; and as the supply of gasoline is used and its level within the tank A cor-

respondingly lowered, the combined float and strainer will fall with the level of the gasoline, the oscillating hub G , in which the lower end of the delivery pipe H is secured, and the segmental opening i^2 in the cylindrical housing which incloses and supports said hub, permitting such movement of the parts. The gasoline is obliged to pass through the strainer J , in order to escape from the tank A through the delivery pipe H , and said strainer not only serves to exclude all sediment and similar foreign matter from the gasoline delivered from the tank, but all water as well, since when the surface of the strainer J is once wet with gasoline no water will pass through it.

In the construction shown in Figs. 1, 2 and 3, and above described, the base plate C , which carries the casting F and delivery pipe H and float and strainer J , is secured directly and permanently to the bottom of the tank A , so that access to the float and strainer, or the other parts carried by the plate C , can be had only through some other opening in the tank A . In the modified construction shown in Figs. 4, 5 and 6, however, the base plate C is detachably secured to the bottom of the tank A , and can be readily removed, and the parts carried by it, including the delivery pipe and float and strainer, be withdrawn through the opening in the bottom of the tank which is closed by said plate when the latter is in place. To this end, in the construction shown in Figs. 4, 5 and 6, I permanently secure to the bottom of the tank A , by brazing or otherwise, an annular attaching plate K having around its inner edge a circular shoulder k which projects upward into and fits snugly within the opening B in the bottom of the tank A , as shown in Figs. 5 and 6. This attaching plate K is provided upon its underside with a series of integral depending threaded bolts L which pass through coincident holes formed for them in the base plate C , which latter is secured in position upon said bolts by nuts M . A packing ring N , formed of a material impervious to gasoline, such as pig-skin, is interposed between the upper surface of the plate C and the attaching plate K , to prevent escape of gasoline from the tank through the joint between said plates. The lower ends of the nuts M are radially notched, as shown in Figs. 4 and 5, and the bolts L are provided with diametrical holes through which cotter pins, fitting in the notches in the nuts, are passed, to prevent unscrewing of the nuts.

As will be understood from the foregoing description, I have provided, in the modified construction shown in Figs. 4, 5 and 6, a construction in which the advantages of that shown in Figs. 2 and 3 are retained, and in which the additional advantage of having the base plate detachable, and permit-

ting the withdrawal of the parts carried by it through the opening in the bottom of the tank, is attained, which is a matter of very considerable convenience in some instances.

5 Having thus fully described my invention, I claim:

1. A mounting for the support of a pivoted oscillating delivery pipe for gasolene tanks and the like comprising a base plate 10 secured to the bottom of the tank and serving to close an opening therein, a casting carried by said base plate and extending upward through said opening into the tank and provided with a delivery passage leading through said plate, and a pivotal support for the lower end of the delivery pipe having its bearings in said casting and provided with a passage communicating with the delivery pipe and with the passage in 15 the casting; substantially as described.

2. A mounting for the support of a pivoted oscillating delivery pipe for gasolene tanks and the like comprising a base plate 20 detachably secured to the bottom of the tank and serving to close an opening therein, a casting carried by said base plate and extending upward through the opening in the attaching plate and bottom of the tank to the interior thereof, and having a delivery passage 25 leading through the base plate, and a pivotal support for the lower end of the delivery pipe mounted in said casting and provided with a passage communicating with the delivery pipe and with the delivery passage 30 in the casting; substantially as described.

3. A mounting for the support of a pivoted oscillating delivery pipe for gasolene tanks and the like comprising the base, a 35 base plate C detachably secured to the bottom of the tank and serving to close an opening therethrough, a casting F carried by the plate C and extending upward through the opening in the attaching plate and bottom 40 of the tank to the interior thereof, said casting being formed with a housing at its top and having a delivery passage leading through the base plate, a hub G having a bearing in said housing formed in said casting F, a delivery pipe H having its lower 45 end secured to and carried by said hub and communicating with the passage leading through the same and connecting with the delivery passage in the casting F; substantially as described.

4. A mounting for the support of a pivoted oscillating delivery pipe for gasolene tanks and the like comprising an attaching plate K permanently secured to the bottom 50 of the tank and having an opening coincident with an opening B in the latter, a plate C detachably secured to the plate K and formed with a depending internally and externally threaded tubular boss E, a casting 55 F carried by the plate C and extending up-

ward through the opening in the attaching plate and bottom of the tank to the interior thereof, said casting being formed with a housing at its top and having a delivery passage leading through said plate C, a hub G 70 having a bearing in said housing formed in the casting F, a delivery pipe H having its lower end secured to and carried by said hub and communicating with the passage leading through the same and connecting 75 with the delivery passage in the casting F; substantially as described.

5. A mounting for the support of a pivoted oscillating delivery pipe for gasolene tanks and the like comprising the plate C detachably secured to the bottom of the tank and formed with a depending internally and externally threaded tubular boss E and a second internally threaded boss D, a casting F having its externally threaded lower end 80 screwed into the internally threaded upper end of the boss E and extending upward through the opening in the attaching plate and bottom of the tank to the interior thereof, said casting being formed with the laterally disposed housing f' at its top and having a delivery passage through it, a hub G having its bearing in the laterally disposed housing f' of the casting F and having connecting radial and axial passages, the latter 85 communicating with the passage through the casting F, a delivery pipe H secured to and carried by the hub G and communicating with the passages extending through it, and a drain cock d secured in the boss D of 90 the plate C; substantially as described.

6. A mounting for the support of a pivoted oscillating delivery pipe for gasolene tanks and the like, comprising an attaching plate K secured to the bottom of the tank 105 and having an opening coincident with an opening B therein, said plate K having depending threaded bolts L, a plate C fitting against the under side of the plate K, and provided with openings coincident with the bolts L, through which openings said bolts pass, nuts M applied to said bolts to secure the plate C in position, a casting F carried by the plate C and extending upward 110 through the openings in the plate K and bottom of the tank into the interior of the latter, said casting having at its upper end an oscillating bearing for the delivery pipe and being provided with delivery passages extending through said oscillating bearing 115 and communicating with the delivery pipe.

7. A mounting for the support of a pivoted oscillating delivery pipe for gasolene tanks and the like, comprising an attaching plate K secured to the under side of the tank 120 coincident with an opening B therein and provided upon its under side with depending threaded bolts L, a plate C fitting against the under side of the plate K and serving to close the opening through the 125 130

same and through the bottom of the tank, said plate C having openings coincident with the bolts L through which the latter pass, a packing ring N, formed of material impervious to gasoline, interposed between the plates K and C, nuts M applied to the bolts L for securing the plate C in position, and a casting F carried by the plate C and extending upward through the openings in the plate K and bottom of the tank to the interior of the latter, said casting having at its upper end an oscillating bearing for the delivery pipe and being provided with delivery passages extending through said oscillating bearing and communicating with the delivery pipe.

8. A mounting for the support of a pivoted oscillating delivery pipe for gasoline tanks and the like, comprising an attaching plate K secured to the bottom of the tank and having an opening coincident with an opening B therein, and provided with de-

pending threaded bolts L, a plate C fitting against the under side of the plate K and serving to close the opening therethrough and through the bottom of the tank, and provided with holes coincident with the bolts L through which the latter pass, nuts M applied to the bolts L, said nuts M provided with diametrically disposed notches, cotter pins passed through holes in the bolts L and engaging said notches in the nuts M, and a casting F carried by the plate C and extending upward into the interior of the tank, said casting having at its upper end an oscillating bearing for the delivery pipe and being provided with delivery passages extending through said oscillating bearing and communicating with the delivery pipe.
